(57) **CLAIM**

The ornamental design for a drink can as shown and
described.

DESCRIPTION

FIG. 1 is a top perspective view illustrating a drink can.

FIG. 2 is a bottom perspective view illustrating the drink can
of FIG. 1.

FIG. 3 is a side view of the drink can of FIG. 1.

FIG. 4 is a top view of the drink can of FIG. 1.

FIG. 5 is a bottom view of the drink can of FIG. 1; and,
FIG. 6 is a side cross-sectional view of the drink can of FIG.
1.

The drink can is shown with dot-dash symbolic breaks in its
length in FIGS. 1-3 and 6. It is understood that patentability
is based only on those portions of the article that are shown
in solid lines, and the appearance of any portion of the article
between the break forms no part of the claimed design.

The portions of the drink can shown in broken lines are
included for the purpose of illustrating environment and
form no part of the claimed design. The portions of the drink
can shown in broken lines having unequal length segments
illustrate the boundary of the claimed design and form no
part of the claimed design.
